TILE CUTTER

Max L. Green, Pasadena, Calif., assignor to Relton Corporation, Pasadena, Calif., a corporation of California
Filed Oct. 15, 1962, Ser. No. 230,652
5 Claims. (Cl. 77—69)

This invention relates to a device for cutting from floor coverings, such as linoleum or asphalt tile, plugs that can be replaced with a minimum of evidence that the floor has been cut.

In treating a structure chemically to exterminate and protect against such pests as termites, it is frequently necessary to drill through the floor of the structure so that chemicals can be injected into the area to be treated. If the wooden or concrete floor has a covering, such as linoleum or asphalt tile, the pest control operator must either remove a portion of the covering prior to actual drilling of the floor or drill through such covering as well as the floor. Conventionally, when removal of covering is the course followed, the pest control operator uses a chisel, or other sharp tool, to chip out a piece of the floor covering. The covering is nearly always cemented to the floor, and the chipping process generally results in not only an irregularly shaped hole in the covering but in fragmentation of the covering section removed. Thus, when the treating job is finished, the operator must (1) either leave the covering with an unsightly hole, (2) attempt to fill the hole with the assembled fragments of the removed but broken section, or (3) if the covering is comprised of squares of tile, attempt to replace with a new square or squares the entire square or squares of tile damaged by removal of the destroyed section. As noted, alternative (1) leaves an unsightly hole in the covering; alternative (2) is time-consuming and results in a very visible patch in the covering; not only is alternative (3) expensive because it is time-consuming to try to find a pattern in new tile that matches tile that was purchased some time previously, but new tile of the same basic pattern often appears to be a conspicuous mis-match with the old tile because of wear which marks the old squares very distinguishably from adjacent new squares.

It is evident that if the operator chooses to drill through the covering, rather than try to remove a replaceable piece, he will destroy the covering drilled through and be faced with the unsatisfactory alternatives described above as (1) and (3).

The primary object of my invention is to enable the pest control operator to cut in a floor covering, such as linoleum or asphalt tile, a plug which can be removed easily without damage from the precise spot desired and can be replaced easily so that only a hairline crack is visible, thus helping to ensure customer satisfaction with the appearance of the finished job without prohibitive time expenditure by the pest control operator. A secondary object of my invention is to prevent, by the coordination of relevant measurements of the parts of the invention, the tool used to cut the floor covering from encountering the underlying floor in such a way as to dull or chip the cutting edge of the tool.

The invention will be more clearly understood from the following description thereof taken in conjunction with the accompanying drawings, in which:

FIGURE 1 is an elevation, partly in section, of the floor covering cutter;

FIGURE 2 is an elevation of the floor covering cutter;

FIGURE 3 is an elevation, partly in section, of the pilot plate;

FIGURE 4 is a top view of the pilot plate; and

FIGURE 5 is a top view of the floor covering cutter from the shank end.

2

FIGURE 1 illustrates the floor covering cutter comprised of the cutter head portion 1 and shank portion 2. The shank is inserted into the chuck of the ordinary electric or air drill; the pest control operator then presses the cutter head edge 3 of the cutting head against the selected spot in the floor tile covering and, while continuing to apply pressure, rotates the cutter by operating the drill motor. The cutter quickly penetrates the floor covering, cutting a fine line around the plug; the operator then heats the plug with a blow torch or other suitable means to soften the mastic holding it to the underlying floor and the plug can then be removed and ultimately replaced.

However, unless a timely stopping of the penetrating forward movement is accomplished, the cutter edge will generally strike the floor underlying the covering and will be quickly dulled or permanently damaged. Therefore, my invention comprises also the pilot plate illustrated in FIGURE 3. The pilot plate is provided with pilot holes 7, 8, 9, 10 and 11 which serve a dual purpose. First, because the internal diameter 12 of each hole is just slightly greater than the outside diameter of the cutting edge 3, the cutting edge can be inserted into the selected pilot hole which has been placed over the spot chosen for the hole to be drilled; then, while the operator holds the pilot plate firmly in place with his foot, the cutting head can be rotated freely in the guiding pilot hole and made to cut the floor covering at the precise spot desired. It will be noted that the cutter head is provided with a shoulder 5 at the transitional point between the cutter head edge and the cutter head body 4, and that, while the diameter of the cutter head edge is such that it can easily be inserted into the smallest diameter portion 12 of the pilot holes, the cutter head body is of such greater diameter that it will enter only the counterbored portion 13 of the pilot holes. Thus, penetration of the cutter head through the pilot holes is abruptly stopped when the shoulder of the cutter head body encounters the transitional shoulder 14 of FIGURE 3 between the counterbored and non-counterbored portions of the pilot holes or encounters the pilot plate itself when the pilot hole has not been counterbored 11.

The cutter head edge is longer than the pilot plate is thick, and will therefore protrude from even a non-counterbored hole if it is pushed through until the shoulder of the cutter head body contacts the pilot plate; but it is obvious that minimum depth of penetration will be obtained by using the non-counterbored hole and maximum depth of penetration will be obtained when the hole that has been counterbored to the greatest depth is used. My invention relates the precise length of the cutter head edge to the thickness of the pilot plate and to the depth of counterboring of the various holes so that by choosing the proper pilot hole the operator can obtain a depth of cutter head edge penetration that will enable him to cut through the specifically-dimensioned floor covering with which he is dealing without damaging contact with the underlying floor.

Each cutter head pilot hole is identified 18 with a number; the numbers correspond to those shown on an instruction sheet as identifying a specific thickness of floor covering. Thus, knowing the covering thickness, the operator selects the number opposite that thickness on the instruction list and then chooses the pilot plate hole which is identified by that number.

FIGURES 1 and 5 show a small hole 6 leading from the back of the cutter head into the cored body 20 of the cutter head. When, as occasionally occurs, the floor covering plug lodges in the cutter-head core-body opening, a nail or similar object of suitable dimension can be inserted from the back of the cutter head through the hole 6 to push the plug out of the core-body opening.

After considerable cutting use, the cutter head edge will be dulled. Attached to the pilot plate, as shown in FIGURE 3, is a sharpening stone 15. To sharpen the cutter head edge, the operator must merely place the cutter head edge over the sharpening stone and apply very gentle downward pressure as he rotates the drill motor chuck which holds the cutter shank. As repeated sharpenings will reduce the length of the cutter head edge, the operator must compensate for such shortening by selecting pilot plate holes with increasingly greater depth of counterbore.

Also shown in FIGURE 3 are drill pilot holes 16 and 17 provided for the convenience of the operator. Certain popular types of masonry drills tend to pivot on their cutters when they are being started, and in doing so they "walk" away from the desired drilling spot. The operator places the drill pilot holes over the desired drilling spot and inserts the masonry drill through the properly dimensioned hole while he stands on the pilot plate to hold it firmly in space to guide the drill as he starts it into the concrete at the selected spot.

I claim:

1. A device for cutting replaceable plugs in floor coverings, said device consisting of a cutter and a pilot plate; the cutter is comprised of a shank end to be held in a rotating device, joined to a round head end, the leading edge of which is sufficiently sharp to penetrate ordinary floor coverings such as linoleum or asphalt tile when the cutter is rotated and pressed against the floor covering and the body of which is provided with a shoulder at the transition point between the lesser diameter of the cutting edge portion of the cutter head and the greater diameter of the remainder of the cutter head and with a hole leading from some point on the cutter head back of the cutting edge into the hollow center of the cutter head so that an implement can be inserted through such hole and into the hollow head to dislodge such floor covering plugs as may lodge there after they have been cut; the pilot plate is comprised of a plate of steel or other suitably abrasion-resistant and rigid material, in which holes have been formed of such minimum diameter that they confine the inserted cutter edge during its rotation and fix its cutting location as the cutter operator holds the plate in selected place, said holes also being of such overall depth and counterbored depth and diameter that the hole properly selected in contemplation of the floor covering thickness will operate in conjunction with the shoulder of the cutter head to stop the forward movement of the cutter edge after it has completely cut through the floor covering but before it has made damaging contact with the underlying floor.

2. A device for cutting replaceable plugs in floor coverings, said device consisting of a cutter and a pilot plate; the cutter is comprised of a shank end to be held in a rotating device, joined to a round head end, the leading edge of which is sufficiently sharp to penetrate ordinary floor coverings such as linoleum or asphalt tile when the cutter is rotated and pressed against the floor covering and the body of which is provided with a shoulder at the transition point between the lesser diameter of the cutting edge portion of the cutter head and the greater diameter of the remainder of the cutter head and with a hole leading from some point on the cutter head back of the cutting edge into the hollow center of the cutter head so that an implement can be inserted through such hole and into the hollow head to dislodge such floor covering plugs as may lodge there after they have been cut; the pilot plate is comprised of a plate of steel or other suitably abrasion-resistant and rigid material, in which holes have been formed of such minimum diameter that they confine the inserted cutter edge during its rotation and fix its cutting location as the cutter operator holds the plate in selected place, said holes also being of such overall depth and counterbored depth and diameter that the hole properly selected in contemplation of the floor covering thickness

will operate in conjunction with the shoulder of the cutter head to stop the forward movement of the cutter edge after it has completely cut through the floor covering but before it has made damaging contact with the underlying floor; in addition to the pilot holes for the guidance and stoppage of the plug cutter the pilot plate is provided with a cutter-edge sharpening stone against which the cutter edge can be gently pressed while being rotated to provide a sharpening result, said stone being affixed to the pilot plate by means of a threaded shank.

3. A device for cutting replaceable plugs in floor coverings, said device consisting of a cutter and a pilot plate; the cutter is comprised of a shank end to be held in a rotating device, joined to a round head end, the leading edge of which is sufficiently sharp to penetrate ordinary floor coverings such as linoleum or asphalt tile when the cutter is rotated and pressed against the floor coverings and the body of which is provided with a shoulder at the transition point between the lesser diameter of the cutting edge portion of the cutter head and the greater diameter of the remainder of the cutter head and with a hole leading from some point on the cutter head back of the cutting edge into the hollow center of the cutter head so that an implement can be inserted through such hole and into the hollow head to dislodge such floor covering plugs as may lodge there after they have been cut; the pilot plate is comprised of a plate of steel or other suitably abrasion-resistant and rigid material, in which holes have been formed of such minimum diameter that they confine the inserted cutter edge during its rotation and fix its cutting location as the cutter operator holds the plate in selected place, said holes also being of such overall depth and counterbored depth and diameter that the hole properly selected in contemplation of the floor covering thickness will operate in conjunction with the shoulder of the cutter head to stop the forward movement of the cutter edge after it has completely cut through the floor covering but before it has made damaging contact with the underlying floor; in addition to the pilot holes for the guidance and stoppage of the plug cutter the pilot plate is provided with a cutter-edge sharpening stone against which the cutter edge can be gently pressed while being rotated to provide a sharpening result, said stone being affixed to the pilot plate by means of a threaded shank.

4. A device for cutting replaceable plugs in floor coverings, said device consisting of a cutter and a pilot plate; the cutter is comprised of a shank end to be held in a rotating device, joined to a round head end, the leading edge of which is sufficiently sharp to penetrate ordinary floor coverings such as linoleum or asphalt tile when the cutter is rotated and pressed against the floor covering and the body of which is provided with a shoulder at the transition point between the lesser diameter of the cutting edge portion of the cutter head and the greater diameter of the remainder of the cutter head and with a hole leading from some point on the cutter head back of the cutting edge into the hollow center of the cutter head so that an implement can be inserted through such hole and into the hollow head to dislodge such floor covering plugs as may lodge there after they have been cut; the pilot plate is comprised of a plate of steel or other suitably abrasion-resistant and rigid material, in which holes have been formed of such minimum diameter that they confine the inserted cutter edge during its rotation and fix its cutting location as the cutter operator holds the plate in selected place, said holes also being of such overall depth and counterbored depth and diameter that the hole properly selected in contemplation of the floor covering thickness will operate in conjunction with the shoulder of the cutter head to stop the forward movement of the cutter edge after it has completely cut through the floor covering but before it has made damaging contact with the underlying floor; in addition to the pilot holes for the guidance and stoppage of the plug cutter the pilot plate

is provided with a cutter-edge sharpening stone against which the cutter edge can be gently pressed while being rotated to provide a sharpening result, said stone being affixed to the pilot plate by means of a threaded shank; the pilot plate is further provided with at least one hole to serve as a pilot hole for starting and temporarily guiding a masonry drill which is used for drilling through the underlying floor when said floor is of masonry construction.

5. A device for cutting replaceable plugs in floor coverings, said device consisting of a cutter and a pilot plate; the cutter is comprised of a shank end to be held in a rotating device, joined to a round head end, the leading edge of which is sufficiently sharp to penetrate ordinary floor coverings such as linoleum or asphalt tile when the cutter is rotated and pressed against the floor covering and the body of which is provided with a shoulder at the transition point between the lesser diameter of the cutting edge portion of the cutter head and the greater diameter of the remainder of the cutter head and with a hole leading from some point on the cutter head back of the cutting edge into the hollow center of the cutter head so that an implement can be inserted through such hole and into the hollow head to dislodge such floor covering plugs as may lodge there after they have been cut; the pilot 25

plate is comprised of a plate of steel or other suitably abrasion-resistant and rigid material, in which holes have been formed of such minimum diameter that they confine the inserted cutter edge during its rotation and fix its cutting location as the cutter operator holds the plate in selected place, said holes also being of such overall depth and counterbored depth and diameter that the hole properly selected in contemplation of the floor covering thickness will operate in conjunction with the shoulder of the cutter head to stop the forward movement of the cutter edge after it has completely cut through the floor covering but before it has made damaging contact with the underlying floor; in addition to the pilot holes for the guidance and stoppage of the plug cutter the pilot plate is provided with a cutter-edge sharpening stone against which the cutter edge can be gently pressed while being rotated to provide a sharpening result, said stone being affixed to the pilot plate by means of a short shank portion brazed to the pilot plate; the pilot plate is further provided with at least one hole to serve as a pilot hole for starting and temporarily guiding a masonry drill which is used for drilling through the underlying floor when said floor is of masonry construction.
